LOOM SHUTTLE

Oscar V. Payne, Leicester, Mass., assignor to
 Crompton & Knowles Loom Works, Worcester,
 Mass., a corporation of Massachusetts

Application August 9, 1934, Serial No. 739,083

2 Claims. (Cl. 139—209)

This invention relates to loom shuttles and is a continuation in part of my prior application Serial No. 650,834, filed by me January 9, 1933, and issued as Patent No. 1,977,083.

5 It is the general object of my invention to provide an improved shuttle for use in a loom having mechanism for indicating the condition of the weft supply in the running shuttle.

More specifically my invention relates to special features in a loom shuttle by which a pneumatic indication of the condition of weft supply may be given without contact of the weft by any moving or mechanical part.

10 My invention further relates to arrangements and combinations of parts which will be herein-after described and more particularly pointed out in the appended claims.

Preferred forms of the invention are shown in the drawings, in which

15 Fig. 1 is a plan view, partly in section, of a shuttle embodying my invention, together with certain associated loom parts;

Fig. 2 is a sectional side elevation, taken along the line 2—2 in Fig. 1;

20 Fig. 3 is an enlarged sectional elevation, taken along the line 3—3 in Fig. 2;

Fig. 4 is a sectional side elevation showing a second form of my invention;

25 Fig. 5 is a detail plan view, looking in the direction of the arrow 5 in Fig. 4;

Fig. 6 is an enlarged sectional elevation, taken along the line 6—6 in Fig. 4;

Fig. 7 is a plan view showing a third form of my invention;

30 Fig. 8 is a sectional side elevation, taken along the line 8—8 in Fig. 7, and

Fig. 9 is an enlarged sectional elevation, taken along the line 9—9 in Fig. 8.

35 Referring to Figs. 1 to 3, I have shown a portion of a lay 10 having a back box plate 11, front binder 12 and picker 13 which provide a box for the shuttle S. The shuttle S is of a usual type and is shown as provided with guides 14 and 15 through which the weft W is threaded.

40 The weft W is indicated as wound on a cop tube 20 having a slot 21 disposed at one side thereof and near the base of the cop. A sleeve 22 of thin rubber or other similar and suitable material is mounted on the cop tube 20 and covers the slot 50 21.

45 The cop tube 20 is positioned in the shuttle S by placing the tube on a spindle 25 having a head 26 (Fig. 2) resting on a block 27 and transversely grooved to receive a pivotal projecting portion 55 or rib 28 on the block 27.

The upper face of the head 26 is formed with two oppositely inclined faces 29 and is engaged by a flat spring 30 which is secured in a recess in the top of the shuttle by a screw 31. The apex 32 of the spindle head 26 is off-center with respect to the pivotal projection 28, so that the spring 30 holds the spindle firmly in horizontal position during loom operation, as clearly indicated in Fig. 2.

5 When the weft supply is to be replenished, the spindle 25 is swung partially upward and the spring 30 engages one of the inclined faces 29 to hold the spindle in upwardly inclined position during the replacement of the exhausted weft carrier.

10 The spindle 25 is provided with a recess 40 in its base 26 and with an axial passage 41 communicating with a transverse passage 42. The transverse passage 42 communicates with a segmental recess 43 in the surface of the spindle 25, so that a continuous air passage is formed through the recess 40, axial passage 41, transverse opening 42 and segmental recess 43 to the slot 21 in the cop tube 20. The cop tube may have a mark 44 (Fig. 5) to assist in approximately aligning the slot 21 with the opening 42 and recess 43.

15 An air container, preferably in the form of a rubber ball 45, is mounted in a recess in the shuttle S below the spring 30 and is provided with an extension 46 snugly fitting in the recess 40 and having an axial passage 47 communicating with the passage 41 in the spindle 25.

20 The shuttle S is also provided with an opening 48 in the side of the shuttle through which a yieldingly mounted plunger 50 may enter and engage the ball 45 as the lay approaches front center. The plunger 50 is mounted on the loom frame 51 and is electrically connected to give an indication of weft exhaustion when the lay 40 reaches front center, unless the plunger 50 is displaced forwardly by the rubber ball 45 so that the contact screw 52 will not engage a contact plate 53 on the front face of the binder 12.

25 For the purposes of this application it is sufficient to state that if the ball resists deflation, the plunger 50 is moved forward with the lay, and the contact screw 52 is held out of engagement with a contact plate 53 on the front of the binder 12. If, on the other hand, the ball 45 does not resist deflation, the parts remain in the position shown in Fig. 1, with the screw 52 engaging the plate 53 and completing an electrical circuit by which loom stoppage is effected. A more complete description of this indicating mechanism 55

will be found in my prior application above identified.

When the active shuttle **S** contains a weft carrier or cop tube having a sufficient supply of weft **W** thereon, the rubber sleeve **22** is held tightly over the slot **21** and is held in close engagement with the cop tube **20** at both ends of the slot **21**. Accordingly, the air in the ball **45** is unable to escape rapidly when the ball is engaged by the plunger **50**, and consequently the plunger **50** is moved forward, and thereby prevents contact of the screw **52** with the plate **53**.

When the weft supply is substantially exhausted, as indicated in Fig. 1, there will remain only a few turns of weft at the extreme bottom of the cop tube **20** and overlying the bottom end only of the rubber sleeve **22**. Consequently, when the ball **45** is then engaged by the plunger **50**, the ball is rapidly and partially deflated, either by escape of air from the free end of the sleeve **22**, or by the outward expansion of the thin sleeve **22**, as indicated in Fig. 1. In either event, sufficient air escapes quickly from the ball **45** to permit the screw **52** to engage the contact plate **53** and thereby complete the electrical circuit which causes stoppage of the loom.

When the shuttle **S** is at the opposite side of the loom, a supplemental contact is opened in the electrical circuit, so that engagement of the screw **52** with the plate **53** will not then complete the circuit and give an undesired indication.

My improved detecting mechanism is particularly desirable for use with silk or other fine or delicate weft threads, as no mechanical element engages the weft in the detecting operation, as has been customary in weft detectors previously in commercial use. The operation of the detecting mechanism depends entirely on the retention or rapid escape of air from the rubber ball **45**, and such rapid escape of air is directly controlled by the presence or absence of the final layer of weft windings about the middle and left-hand portions of the rubber sleeve **22** (as viewed in Figs. 1 and 2).

In Figs. 4, 5, and 6 I have shown the adaptation of my invention to a type of spindle in which the spindle blade **60** is provided with a resilient portion **61** yieldingly engaging the inner surface of the cop tube **20** and preventing axial displacement thereof.

The construction is substantially the same as that previously described, except that the air passage **62**, transverse passage **63**, and segmental re-

cess **64** (Fig. 6) are all formed in the solid portion of the spindle blade **60** and above the slot **65**. Otherwise the construction and operation is identical with that previously described.

It may be noted, however, that the weft in Figs. 4 and 5 is shown as substantially exhausted and the rubber tube **22** is shown as forced outward in Fig. 4, indicating that the ball **45** has been partially deflated to give an indication of weft exhaustion.

In Figs. 7, 8, and 9 I have shown a third form of my invention in which the surface of the spindle **70** is provided with a helical rib **71** in the portion adjacent the lateral air openings **72** which connect with the longitudinal air passage **73**. With this construction the rib **71** holds the inner surface of the cop tube **20** spaced from the spindle **70** sufficiently to allow air to circulate entirely around the spindle and it is thus unnecessary to provide the segmental recess in the body of the spindle as shown in the previous forms.

I have shown two lateral openings **72** but more or less openings may be used as seems advisable.

The use and operation of this form of my invention is identical with those previously described. In the drawings I have shown the spindle **70** as a solid spindle, whereas in Fig. 1 the spindle **25** is shown as provided with a longitudinal slit **25a**. Both of these forms of spindles are old and well known and for the purposes of my invention may be considered interchangeable.

Having thus described my invention and the advantages thereof, I do not wish to be limited to the details herein disclosed, otherwise than as set forth in the claims, but what I claim is:—

1. In a loom shuttle, a spindle having a head with a transverse groove in one lateral face and an inclined face at the opposite side of said head, a block in said shuttle having a rib seated in said groove, and a spring positioned to engage said inclined face and hold said spindle in raised position.
2. In a loom shuttle, a spindle having a head with a transverse groove in one lateral face and an inclined face at the opposite side of said head, a block in said shuttle having a rib seated in said groove, and a spring positioned to engage said inclined face and hold said spindle in raised position, said spring also engaging said head when in lowered position at a point offset toward the tip of the spindle from said transverse groove.

OSCAR V. PAYNE.
